DESIGN FOR A SHOE

Richard P. Boothby, Auburn, Maine

Application May 29, 1941, Serial No. 101,225

Term of patent 7 years

To whom it may concern:

Be it known that I, Richard P. Boothby, a citizen of the United States and a resident of Auburn, Maine, in the county of Androscoggin and State of Maine, have invented a new, original, and ornamental Design for a Shoe, if which the following is a specification, reference being had to the accompanying drawing, forming a part thereof, in which:

Fig. 1 is a plan view of a shoe showing my new design, and

Fig. 2 is a side elevational view thereof.

In both views the heel end of the shoe is shown conventionally in dot and dash lines.

The dominant features of my design consist in the perforated cross in the vamp and in the quarters as well as the group of perforations in the instep.

I claim:

The ornamental design for a shoe, substantially as shown and described.

RICHARD P. BOOTHBY.
